UNITED STATES PATENT OFFICE.

WILLIAM L. PARKER, OF PALO ALTO, AND ELY C. HUTCHINSON, OF OAKLAND, CALIFORNIA, ASSIGNORS TO PELTON WATER WHEEL CO., OF SAN FRANCISCO, CALIFORNIA, A CORPORATION OF CALIFORNIA.

HYDRAULIC NOZZLE.

Application filed November 1, 1922. Serial No. 598,310.

To all whom it may concern:

Be it known that we, WILLIAM L. PARKER and ELY C. HUTCHINSON, the said PARKER

a citizen of New Zealand, and the said

5 HUTCHINSON a citizen of the United States, residing, the said PARKER at Palo Alto, in the county of Santa Clara and State of California, and the said HUTCHINSON at Oakland, county of Alameda, State of California, have invented certain new and useful Improvements in Hydraulic Nozzles, of

which the following is a specification.

The present invention relates to an hydraulic nozzle and needle valve construction designed to enable the nozzle to be positioned with its discharge end in close proximity to the periphery of the water wheel runner and buckets, and at the same time permitting of the demounting of the 10 nozzle and needle valve when it is desired to renew the worn parts thereof.

Heretofore it has been necessary to position the discharge end of the nozzle some distance from the periphery of the water 15 wheel and buckets in order that the nozzle and needle parts when worn could be readily replaced, which construction has occasioned considerable loss in power, due to the distance between the discharge end of the nozzle and the periphery of the wheel, which 20 has been necessary to enable the making of repairs.

By our present construction, which consists primarily in dividing the needle valve 25 and discharge end of the nozzle body transversely into co-operating separable sections, we are enabled to position the discharge end or nozzle tip of an hydraulic nozzle body in extreme close proximity to 30 the path of travel of the wheel buckets to obtain the maximum power from the issuing stream, and to enable the ready dismantling of the discharge tip and needle valve for the replacement of the worn parts 35 thereof without affecting the position of the wheel or nozzle body.

With the above mentioned and other objects in view, the invention consists in the novel construction and combination of parts 40 hereinafter described, illustrated in the accompanying drawings and pointed out in the claims hereto appended; it being understood that various changes in the form, proportion, size and minor details of construc-

tion within the scope of the claims may be 55 resorted to without departing from the spirit or sacrificing any of the advantages of the invention.

To more clearly comprehend the invention, reference is directed to the accompanying drawings, wherein:

Fig. 1 is a longitudinal sectional view of the preferred embodiment of our invention disclosing the nozzle tip and sectional needle valve.

Fig. 2 is a view in end elevation partly in section, taken on line 2—2 of Fig. 1.

Fig. 3 is a view in side elevation disclosing the nozzle tip detached from the body and the needle point mounted on the end of 70 the tie rod.

Referring more particularly to the drawings, wherein like characters of reference designate corresponding parts—1 indicates a tubular nozzle body provided with a water inlet opening 2 at one side thereof and a discharge opening 3 at the end of the body. The opening 3 is surrounded by a flange 4 and over the opening is removably positioned a nozzle tip 5 annularly flanged at 75 its base, as at 6, and retained in position over the discharge opening 3 by a sectional retaining ring 7. Through openings in the retaining ring are adapted to pass the retaining studs 8 carried by said flange and nuts 9 are adapted to force the ring towards said flange 4 and cause the engagement of the ring flange 10 to co-operate with the flange 6 to provide a leak-proof joint between the edge of the nozzle tip 5 80 and the opening 3.

The nozzle tip which terminates in the discharge opening 11 mounts a needle seat ring 12 threaded into or bolted to said discharge opening.

It will be observed that the discharge end of the nozzle body mounts the removable nozzle tip 5 and seat ring 12, the nozzle tip being readily removed from the body by removing the sections of the retaining ring 7 from over the studs 8.

In alignment with the opening 3 the nozzle body 1 is provided with a needle valve guide opening 13 within which is removably held a bearing sleeve 14 in which bearing sleeve is mounted to reciprocate the cylindrical guide end 15 of the regulating valve 16. A gland 17 at the outer end of

the bearing sleeve prevents leakage between the guide end of the valve 16 and the bearing sleeve. The interior of the valve 16 is preferably hollow as at 18 and is provided 5 with a tubular bore 19 disposed longitudinally thereof.

Within the main chamber of the nozzle body 1 the valve 16 is formed with a contracted stem 26 and at its outer end carries 10 the hollow head 27. The head in the present structure is formed in three sections 27, 20 and 21, which provide the well known form of needle tip or valve employed in hydraulic nozzles, and the wall of the section 15 20 is adapted to engage the seat ring 12, as illustrated.

Within the bore 19 and disposed longitudinally of the valve 16 is a tie rod 22 having threaded connection at its outer end 20 with the base of the needle point 21, and said rod, when the same is placed under tension, is adapted to draw the meeting edges of sections 27, 20, 15 and 21 into tight contact. The rear threaded end of 25 the rod 22 extends through an opening in the rear of the guide 15 and on the same is threaded a nut or takeup 23 which when adjusted is adapted to place the rod 22 under tension.

30 On the release of the nut 23 the rod 22 may be rotated to release the forward end thereof from the base of the needle point by the operator imparting rotative movement to the rod by positioning a key or 35 other tool over the polygonal end 24 of the rod. If desired, a lock nut or guard 25 adapted for operating the valve in any desired manner may be secured to the projecting end of the rod 22 and may be constructed to conceal the polygonal end 24 thereof.

40 The regulating valve 16 is usually supported only at its rear end leaving its needle end open and affording but little obstruction to the passage or flow of water through the nozzle.

45 It will be observed that when replacement or repair of the needle end of the regulating valve or of the nozzle tip is necessary, the 50 needle end of the valve may be removed in sections and the nozzle tip may be dismantled in sections and when repairs are effected, the parts may be sectionally assembled.

Having thus described our invention, what 55 we claim as new and desire to protect by Letters Patent is:—

60 1. A needle valve for hydraulic nozzles, including a body having an enlarged head and terminating in a needle point, said head in rear of said needle point being divided transversely into a plurality of separatable sections, and means for detachably securing said sections together with their edges in engaging relation.

2. A needle valve for hydraulic nozzles, 65 including a body having an enlarged head and terminating in a needle point, said head in rear of said needle point being divided transversely into a plurality of separatable sections, and a tie rod disposed longitudinally within said body for detachably uniting 70 said sections.

3. A needle valve for hydraulic nozzles, 75 including a body having an enlarged head terminating in a detachable needle point, said head in rear of said needle point being divided transversely into a plurality of separatable parts, and a tie rod disposed longitudinally within said body and detachably secured to the needle point part of the head, said rod projecting from the rear of said body, and means for creating a tension on said rod for detachably retaining said parts together.

4. A needle valve for hydraulic nozzles, 80 including a cylindrical body, an enlarged needle head carried at one end thereof, said head including a needle point and a plurality of co-operating sections in rear thereof capable of separation one from the other, and means within said body for retaining 85 said sections in assembled relation.

5. An hydraulic nozzle construction comprising a tubular nozzle, a nozzle tip detachably secured to the discharge end of said nozzle, a needle valve seating ring detachably secured to said tip, and a valve within 90 said nozzle formed with a needle head consisting of a needle point and a plurality of separatable sections, one of said sections in rear thereof adapted for seating against 95 said ring.

6. An hydraulic nozzle construction comprising a tubular nozzle formed at one end with a discharge opening, a valve guide 100 chamber at its opposite end in alignment with said discharge opening, a nozzle tip removably positioned over the discharge opening of said nozzle, and a sectional ring for detachably securing said nozzle tip to 110 said nozzle.

7. An hydraulic nozzle construction comprising a tubular nozzle mounting a valve seat ring formed with a discharge opening, a needle valve within said nozzle for controlling said discharge opening, the discharge end of said nozzle adapted for separation on transverse lines into a plurality of co-operating separatable sections, said 115 needle valve at its point of co-operation with said discharge opening being divided transversely into a plurality of interconnected separatable sections, and a guide for said valve.

In testimony whereof we have signed our 120 names to this specification.

WILLIAM L. PARKER.
ELY C. HUTCHINSON.
